UNITED STATES PATENT OFFICE.

FREDERICK J. P. KUHLMANN, OF SAN FRANCISCO, CALIFORNIA, ASSIGNOR TO FLORA KENT, OF OAKLAND, CALIFORNIA.

LOOSE-LEAF BINDER.

1,033,101.

Specification of Letters Patent. Patented July 23, 1912.

Application filed January 11, 1912. Serial No. 670,558.

To all whom it may concern:

Be it known that I, FREDERICK J. P. KUHLMANN, a citizen of the United States, residing at San Francisco, in the county of San Francisco and State of California, have invented new and useful Improvements in Loose-Leaf Binders, of which the following is a specification.

The present invention relates to improvements in loose leaf binders, and especially to that class of binders employed for binding balance sheets and the like, in which the balance sheets can be in either one of two different transverse positions, so that the balance sheet may be secured, when desired, in such a position that one longitudinal marginal portion thereof, preferably the right hand side, can be extended laterally beyond the edges of the remaining sheets, for bookkeeping purposes. It has been the practice heretofore to effect this result by forming each balance sheet with laterally extending slots, each slot having circular ends with a narrow intervening portion. For use with sheets of this character, the yokes upon which the sheets are guided from their forwardly to their rearwardly extending position, are each formed with upright parts circular in cross section but with a connecting arch which in cross section is flattened transversely or horizontally. In this way, the balance sheet can be shifted from one lateral position to the other by raising said sheet, the circular ends of the slots being guided upon the cylindrical posts, until the sheet is brought to the arches, in which position the narrow intermediate parts of the slots can be moved past the thin or flattened arches of the yokes, so that the other circular ends of the slots can engage the posts, the sheet being then lowered again either to the front or rear as may be desired. It has been found that this construction has several disadvantages. Particularly, by reason of the slots being of the form above explained, the paper around the slot is formed with projections on opposite sides of the narrow intermediate portions of the slot. These projections are exposed to considerable wear in passing over the arched portions of the yokes and thus tend to become frayed. Also, it is comparatively easy to shift the balance sheet from one lateral position to another, and therefore the balance sheets may be so shifted accidentally and are not firmly and

positively retained in the position in which they are set.

One object of this invention is to provide a loose leaf binder which will avoid the above objections.

A further object of the invention is to provide such a binder which will be strong and durable.

In the accompanying drawing, the figure is a broken perspective view of a binder of my improved construction.

Referring to the drawing, 1 indicates the back or frame of a binder, on which are erected two fixed posts 2 and in which can turn two movable posts 3, provided at their bases with suitable bearing plates 4. The posts 3 at their upper portions are extended to form arches 5, the lower free ends of which are recessed, as shown at 10, to fit snugly over conical upper ends of the posts 2, said posts 2 and 3, with the arches 5 of the latter, thus forming yokes. Said posts 2 and 3 and arches 5 are circular in cross section and of uniform diameter throughout. Also extending upwardly from said frame are two stems 6, pointed at their upper ends, the forward stem being in the same plane as the two posts 2 and midway between them, and the rear stem being in the same plane as the rear posts 3 and midway between them.

7 indicates a balance sheet, of which there may be any desired number. Said balance sheet is formed near the top and at the longitudinal margins thereof with two slots 8, which are rounded at the ends and of uniform width throughout, said width being just sufficient to conveniently receive the posts 2 or 3. By reason of the posts 2, arches 5 and posts 3 being uniform in circular cross section, said sheet 7 can, when said arches 5 engage the posts 2, very readily move so that its slots, instead of engaging the posts 2, engage the posts 3, or conversely. The balance sheet is likewise formed with two circular holes 9 in line with the slots 8, which are in alinement with each other, and the holes are equi-distant from said slots 8 respectively, the distance between the centers of the two holes being the same as that between the centers of the circular ends of either slot.

The mode of use of the device will very readily be understood from the foregoing description. When it is desired to transfer

from the front posts to the rear a sheet, either a balance sheet, or of other kind, this is done in the ordinary manner, a hole 9 being moved out of engagement with the 5 front stem 6 and coming into engagement with the rear stem 6. But when it is desired to move a balance sheet laterally, the balance sheet is first raised on the posts 2 or 3, whichever of these it is on, until the 10 sheet is clear or free from the corresponding stem 6. It can be then shifted laterally so that the other ends of the respective slots are in engagement with the arches 5. In this position it is then lowered again, a stem 15 6 then engaging the hole 9 other than that which was formerly engaged.

It will be seen that a binder of this construction is free from the defects above noted. There are no projecting edges of 20 paper liable to become frayed by the lateral inmovement of the balance sheet. Also the balance sheet is held positively and firmly, and without any possibility of accidental displacement. Moreover the device is very 25 strong and durable, since the posts and arches may be made of uniform thickness and of circular cross section. Also, by reason of the form of said arches, sheets can be transferred from the front to the rear posts 30 with the least possible friction.

I claim:

1. In combination with a loose leaf binder back having erected thereon a yoke for

transferring sheets from front to rear and also a pair of front and rear stems, a sheet 35 having a slot to be engaged by one of the members of the yoke and having two perforations adapted alternately to be engaged by the corresponding stem.

2. In combination with a loose leaf binder 40 back having a pair of yokes, front and rear stems, intermediate of the yokes, and a sheet having slots adapted to be engaged by corresponding members of said yokes and a pair of holes either of which is adapted to 45 be engaged by either of the stems.

3. The loose leaf binder back having erected thereon yokes, one member of each of which is separable from the other, and front and rear stems between said yokes. 50

4. A sheet having through a marginal portion slots in alignment with each other, and, between said slots, two holes equi-distant from ends of the respective slots and in line with the slots, each slot being of length 55 not less than the sum of the lengths, in the same direction as that of the slots, of the holes and the distance between the holes.

In testimony whereof I have hereunto set my hand in the presence of two subscribing 60 witnesses.

FREDERICK J. P. KUHLMANN.
